Arthur V. Moulton.

UNITED STATES PATENT OFFICE.

HOMER L. BOYLE, OF GRAND RAPIDS, ASSIGNOR OF ONE-HALF TO HORACE B. PECK, OF ALLEGAN, MICHIGAN.

MAIL-BAG FASTENING.

SPECIFICATION forming part of Letters Patent No. 397,689, dated February 12, 1889.

Application filed August 1, 1888. Serial No. 281,686. (No model.)

To all whom it may concern:

Be it known that I, HOMER L. BOYLE, a citizen of the United States, residing at Grand Rapids, in the county of Kent and State of Michigan, have invented certain new and useful Improvements in Fastenings for Mail-Bags; and I do hereby declare the following to be a full, clear, and exact description of the invention, such as will enable others skilled in the art to which it appertains to make and use the same.

My invention relates to improvements in fastenings for mail-bags, which are provided with such fastenings at intervals, such fastenings being finally secured by a lock.

The objects of my invention are to provide a durable and simple device that can be quickly manipulated and to so arrange the parts that they will be protected from injury and not easily accessible from the outside. I accomplish these results by the mechanism illustrated in the accompanying drawings, in which—

Figure 1 represents an elevation of an open mail-bag having attached a device embodying my invention; Fig. 2, a vertical section of the same on the line *x x* of Fig. 1; Fig. 3, the same as Fig. 1 closed; Fig. 4, a vertical section of the same on the line *y y* of Fig. 3, and

Fig. 5 a detail of the T-bolt and arm attached.

Like letters refer to like parts in all the figures.

A is the bag proper, having a flap, *B*, adapted to fold over the end and close the opening in the usual way.

C are plates secured to the side of the bag, having oblong openings *D* to receive the T-bolts *G*, which are attached to the flap *B* (in proper position to engage with said openings *D*) by means of plates *H*, within which said bolts are rotated and held in position by means of the arms *K*, which are attached to the shanks of said bolts and connected at their movable ends by the flexible bar *I*, which bar is operated by the lever-plate *E'*, which is pivoted near one end to the last bolt in the series, and also pivoted to the end of said bar *I*, the relative position of the said pivots being the same as those connecting the arms *K* to the bolts *G* and the bar *I*. The pivot *N* passes through a

curved slot in the outer material of the flap, which slot is covered by the lever-plate *E*. The movable end of the plate *E* is provided with an opening, *F'*, which, when the device is locked, corresponds and coincides with a similar opening, *F*, in a fixed plate, *E*, secured to and projecting from the side of the bag. Through these openings is thrust the hasp of a padlock to secure and lock the device. The bar *I* is made shorter than the width of the bag, so that it and arms *K* are entirely enclosed between parallel pieces of material constituting the flap *B*, which serves to protect said bar and arms and hide them from sight and also to keep the various sections of the bar in line, so that it will operate all the bolts at once. Said bar *I* may be a continuous strip of flexible material or may be a series of rectangular plates hinged to each other to give flexibility. I prefer the latter construction.

L is a chamber behind the plate *C*, within which the head of the T-bolt turns.

If desirable, the plates *C* may be located upon the inner surface of the other side of the bag, allowing the T-bolts to strike through openings in the side next the flap, or plates may be placed in both places and the T-bolts engaged with either series, as most convenient.

The operation of my device is as follows: By rotating the plate *E'* about the pivot *G* all the T-bolts are caused to rotate upon their axes, and when said plate is in the position shown in Fig. 1 the longer dimension of the heads of said bolts corresponds with that of the openings in the plates *C*, and the said heads can be detached from said plates. By closing the flap *B*, inserting the bolts *G* in the openings *D*, and turning the plate *E* a quarter-revolution, as shown in Figs. 3 and 4, the heads of the T-bolts will all be turned at right angles to the openings *D* and engage with the inner surface of the plates *C*. The flap will thus be secured to the side of the bag at each point corresponding to the location of each pair of bolts and plates. The detached character of each fastening, the flexibility of the bar *I*, and the freedom of the shanks of the T-bolts to slide along in the openings *D* render the bag flexible and the fastening devices secure and

not liable to breakage, and when closed and secured the fastening devices are all hidden from sight and protected by the outer material of the flap B, except the plates E' and E and the lock M, which are necessarily accessible. The plate E also operates as a lever and enables me to turn the T-bolts more easily.

What I claim, and wish to secure by Letters Patent, is as follows:

- 10 1. In combination with the body of a mail-bag and the plates C, attached thereto and slotted at D, the flap B, provided with plates H, the T-bolts G G, extending through these plates and adapted to enter said slots, the arms K, attached to said bolts, the bar I, attached to said arms, the plate E', pivoted on said flap and attached to the end of said strap, the plate E, attached to the body of the bag,
- 15

and the padlock M, for locking said plates together, substantially as set forth.

2. A mail-bag having a body, A, and flap B, the latter provided with an interior chamber or space, of a bar moving longitudinally in said space, a series of arms attached to said bar, a series of inwardly-extending T-bolts attached to and operated by said arms, and the body of the mail-bag adapted to be engaged by said T-bolts, the above fastening devices being wholly covered when the bag is closed, substantially as set forth.

In testimony whereof I affix my signature in presence of two witnesses.

HOMER L. BOYLE.
